FUSIBLE LINE TAPPING DEVICE

Carroll H. Walsh, Pine Bluff, Ark., assignor to
 Tips Tool Company, Inc., Taylorville, Ill., a corporation of Illinois

Application March 26, 1934, Serial No. 717,463

5 Claims. (Cl. 200—115.5)

This invention relates to fusible line-tapping devices for connecting electrical apparatus to an overhead electric line, and has for its principal object the provision of a simple, inexpensive and effective device for this purpose.

A further object is the provision of a fusible line-tapping device adapted to clamp on and to be supported by an overhead conductor, in which the fuse and the clamp have parts in common whereby a minimum of parts is required in the construction of the device.

Another object is the provision of means for preventing damage to the fuse tube embodied in the device from creepage current over the surface thereof following the blowing of the fuse from the tube.

A yet further object is the provision of means in a fusible device for facilitating its installation on and removal from a live conductor by means of insulated or "hot line" tools.

With these and other objects in view which will appear as the description proceeds, my invention resides in the novel combination and arrangement of the parts making up the device, to the end that the number of parts is reduced to a minimum by arranging them so that certain of the parts perform a plurality of essential functions.

In the drawing: Figures 1, 2, and 3 are similar elevational views of certain embodiments of the invention, and Figure 4 is a side elevational view of a pole having mounted thereon a piece of electrical apparatus, showing an arrangement including the invention for connecting the apparatus to a line conductor.

Referring now in detail to Figure 1, the numeral 13 designates a tube of insulating material, such as vulcanized fiber, which latter material is commonly used in the construction of expulsion fuses. A hollow conducting electrode 16 is rigidly secured in any suitable manner at the upper end of the tube 13, and an adjustable threaded terminal 19 is provided to cooperate with a threaded opening through a wall of the electrode 16 to engage the upper end of the fuse link 18. The electrode 16 is provided with a transverse groove across a face thereof to provide a seat for a line conductor or wire 10. An adjustable wire-engaging member 17 is pivotally mounted on an upwardly and outwardly extending integral portion of the electrode 16, by means of the pivot 18, the latter extending through an opening in both the members. The wire-engaging member 17 is provided with an outwardly and downwardly curved lower end portion to fa-

cilitate the engagement of the electrode 16 with a line wire. A second integral portion of the electrode 16 extends upwardly and outwardly in a direction substantially normal to the above-mentioned integral portion, and has its upper end portion formed into the eye 14, the latter being adapted to cooperate with an insulated tool for the purpose of hooking the device on a line wire. A threaded opening extends through the last-named integral portion in a direction normal to the wire-engaging member 17, into which is fitted the screw eye 15, the end of which is arranged to engage the upper end of and thereby rotate the member 17 about the pivot 18 for the purpose of clamping the wire 10 between the electrode 16 and the member 17.

Adjacent the lower end of the fuse tube 13 is supported, in any suitable manner, as by means of the concentric ring 24 and the cooperating set screw 25, the insulator 20, of any suitable material having a high leakage and dielectric strength, such as porcelain. By means of a longitudinal opening through the insulator 20, the latter is arranged coaxially and concentrically with the fuse tube 13, and in this manner so distributes the weight of the insulator with respect to the tube that the latter normally assumes a vertical position when the device is hooked over a line conductor. A circumferential groove is provided on the insulator 20, into which is fitted a pair of complementary clamping conducting members 21 and 22, which are maintained in engagement with the groove by means of the screws 23, the latter extending through outwardly extending integral portions of the members 21 and 22. By means of downwardly extending, diametrically spaced integral portions of the clamping members 21 and 22, two terminals are provided adjacent the lower end of the tube and in spaced relationship thereto. The terminal including the bolt 26 and the cooperating nut 27 is provided near the lower end of the clamping member 21 for connecting the load wire 11, and the adjustable threaded terminal 28 is provided near the lower end of the clamping member 22 for connecting the lower end of the fuse link 18; the latter extending upwardly through the fuse tube 13, and being connected to the upper electrode as above described.

In the embodiment illustrated by Figure 2, an arrangement is shown in which the fuse tube 13 is supported near the midpoint, both ends of the tube being open, thus providing a combined support and reinforcement of the tube at the region of maximum stress, and at the same time

eliminating the recoil occasioned by the interruption of high currents.

In this embodiment, the wire-clamping device comprises the hook-shaped conducting member 33, which is provided for hooking the device to the line wire 10, and an eye 29 is formed by an integral portion of the member 33 at the upper end thereof for facilitating the application of the device to a live conductor by means of an insulated tool. A wire-engaging shoe 31 is slidably mounted on one arm of the hook 33, the former being provided with an integral portion 32 extending across the opening of the hook for the purpose of continually maintaining the 10 slidable shoe 31 in engagement with the line wire 10. A threaded opening is provided through and substantially normal to the member 33 for co-operating with the threads of the screw eye 15, the end of the latter being arranged to engage 15 the shoe 31, and, upon rotation of the screw eye 15 in a predetermined direction, to clamp the line wire 10 between one arm of the hook member 33 and the wire-engaging shoe 31.

The hook member 33 is provided with a downwardly extending integral portion 46, at the lower end of which is provided a hollow cylindrical laterally extending integral portion 35, arranged for engaging a portion of the outer surface of the fuse tube 13 near the midpoint thereof. 20 The set screw 36, cooperating with the hollow portion 35 and the tube 13, is provided for rigidly securing the tube in place. A laterally extending flat integral portion of the downwardly extending portion 46 is provided near the upper 25 end of the tube 13 for securing the upper end of a fuse link thereto by means of the adjustable threaded terminal 34.

The insulator 43 is supported in any suitable manner adjacent the lower end of and extending 30 downwardly from the portion 46 by means of an outwardly extending integral portion 40, which extends laterally from the portion 46 in a direction opposite that of the portion 35. The supporting means here shown includes an opening 35 through the portion 40 through which a threaded member secured to the insulator 43 passes, the latter being secured by means of a cooperating nut 41. In this manner the major axes of the tube 13 and the insulator 43 are supported in 40 substantially parallel spaced relationship. A conducting member 47 is secured to the lower end of the insulator 43 in any suitable manner, as by the cap screw 42 extending through the member 47 and into the insulator 43, and is provided 45 with two integral downwardly extending end portions, one of which, in cooperation with the bolt 26 and its cooperating nut 27, provides a terminal for the load wire 11, and the other of which provides, in cooperation with the terminal 28, means for attaching the lower end of the fuse link 38.

In this arrangement, the fusible element of the fuse link 38 is preferably positioned within the tube near the midpoint thereof, so as to substantially balance the recoil in the upper half of the tube 13 against that in the lower half, and at the same time take advantage of the tube reinforcement provided by the hollow portion 35.

In the embodiment shown in Figure 3, the wire clamp is similar to that set out above in the description of Figure 2, and is therefore designated in its entirety by the numeral 37. This embodiment differs from that shown in Figure 2 75 only in the arrangement of the fuse tube and

the insulator with respect to the supporting clamp therefor.

The insulator 43 and the fuse tube 13 are both supported from their respective upper ends from a downwardly extending and laterally folded integral portion of the clamp 37. At the end of the folded portion 30 is formed an integral portion thereof in the shape of an electrode 44, the latter being adapted to support the tube 13 in substantially a vertical position. The adjustable threaded terminal 45 is arranged to cooperate with the electrode 44 to enable, in the usual manner, the passage of a fuse link through the fuse tube 13. In laterally spaced relationship to the tube 13 and substantially parallel thereto is supported the depending insulator 43, as described above in connection with Figure 2. A U-shaped conducting member 48, having one arm of the U secured to the lower end of the insulator 43 by means of the bolt 42, provides means for connecting the fuse link 12 and the load wire 11 thereto, the former by means of the terminal 28, and the latter by means of the bolt 26 and the nut 27.

It will be seen that in both the embodiments 25 illustrated by Figures 2 and 3, the blowing of the fuse links from the tubes in each of these arrangements will remove the fuse tubes from the circuit of which the fuse link was, prior to such blowing, a part.

Referring now to Figure 4, 50 designates the device illustrated in detail in Figure 1, being shown in the service position, connected to and suspended from the line wire 10. The load wire 11 provides a means for connecting the terminal 35 51 of the apparatus 52 to the lower terminal of the line-tapping device. Figure 4 is only for the purpose of illustrating one method of usefully employing the device.

While I have here illustrated and described 40 several embodiments of my invention, other embodiments will appear from those disclosed herein, and it is to be understood that my invention is to be limited only by the appended claims and the prior art.

I claim as my invention:

1. A fusible line-tapping device comprising a clamp of conducting material arranged to co-operate with a line conductor and to be detachably supported thereby, a fuse tube of insulating material open at both ends, means including an integral portion of said clamp for rigidly supporting said tube near the midpoint thereof, an insulator, means combined with one end of said insulator for cooperating with an integral portion of said clamp for rigidly securing said insulator thereto, a terminal adapted to engage a load wire rigidly secured to said insulator adjacent the other end thereof, and means including a fuse link extending through said tube for connecting said clamp to said terminal.

2. A fusible line-tapping device comprising a clamp of conducting material adapted to be removably attached to a line conductor, an insulator rigidly secured to said clamp adjacent the lower end thereof and extending downwardly therefrom, a conducting member secured adjacent the lower end of said insulator, a fuse tube of insulating material open at both ends, means including a laterally-extending integral hollow cylindrical portion of said clamp for supporting said tube adjacent the midpoint thereof whereby the ends of said tube are in spaced relation with respect to the other parts of the device, and means including a fuse link extending through 75

said tube for electrically connecting said clamp to said conducting member.

3. A fusible line-tapping device comprising a clamp of conducting material arranged to operate with a line conductor and to be detachably supported thereby, said clamp having an integral hollow cylindrical portion adjacent the lower end thereof, a fuse tube of insulating material open at both ends extending through said hollow portion, said tube being supported adjacent the midpoint thereof, a fuse link extending through said tube, a load terminal, insulating means supporting said load terminal, means including an integral portion of said clamp for supporting said insulating means, said insulating means normally insulating said clamp and said load terminal, and means including integral portions of said clamp and said load terminal for attaching the respective ends of said fuse link thereto whereby said clamp and said load terminal are electrically connected.
4. A fusible line-tapping device comprising a clamp of conducting material adapted to be removably attached to a line conductor, an insulator rigidly secured to said clamp adjacent the lower end thereof and extending downwardly

therefrom, a conducting member secured adjacent the lower end of said insulator, a fuse tube of insulating material, means including an integral laterally extending portion of said clamp arranged to cooperate with the upper end of said tube for supporting said tube substantially parallel to and spaced from said insulator, said laterally extending portion forming a top electrode on said fuse tube, and means including a fuse link extending through said tube for electrically connecting said clamp to said conducting member.

5. A fusible line-tapping device comprising a clamp of conducting material arranged to removably engage a line wire and to be supported thereby, an insulator secured to said clamp adjacent the lower end thereof and extending downwardly therefrom, a conducting member secured adjacent the lower end of said insulator, means for connecting a load wire to said conducting member, a fuse link, and means including a first detachable terminal carried by said clamp and a second detachable terminal carried by said conducting member for engaging the respective ends of said fuse link.
